BAR METERING SYSTEM

Carolus L. Eksergian, Detroit, Mich., assignor to
Budd Wheel Company, Philadelphia, Pa., a
corporation of Pennsylvania

Application July 31, 1930, Serial No. 472,046

12 Claims. (Cl. 164—48)

This invention consists of a feeding and metering system for bar stock, particularly hot bar stock, which is to be severed in lengths for fabrication. Its most useful application to date has been in connection with great obtuse angled rolling mills for the formation of integral hubs, integral hubs and drums and for the rolling of disc and other wheels from billets of cylindrical bar stock.

10 However, the invention doubtless has other applications both to smaller and to larger operations of different classes of machinery which are most conveniently operated by strip or rod stock, perhaps even sheet stock after the same has been 15 longitudinally cut into parts more conveniently operated upon than the entire bar, etc.

Particularly in the handling of massive bars from three to ten inches in diameter, do the system and method of this invention find utility. 20 Such bars, by reason of their very massiveness, are very difficult to handle, not to mention measure and cut-off with accuracy. Incident to the accumulation of scale, within the furnace in which they are heated for cut-off and the fabricating operations, the bars have a tendency to 25 get out of line with the support and jamb. Likewise, irregularities in succession of feeding of bars within the furnace itself induces irregularities in feeding of the individual bar to the metering and 30 the cut off mechanisms. The extreme temperatures to which such stocks need be raised to put them into condition for the great amount of work necessary to be done upon them by the cut-off, the billet or blank forming, and the final fabrication by rolling, not only introduces an undue 35 amount of scale, but also affects the reliability and accuracy of the ordinary feeding and cut-off devices. The very massiveness of the stock also necessitates highly specialized cut-off devices 40 and the shapes of the cut-off faces of the stock introduce new problems in reverse angular planes for metering. Economical handling of such massive stock without waste of power is likewise a problem.

45 The aims of my invention comprehend the solution of these problems by common means and by means so simple and direct as to reduce first cost and at the same time to further reliability, durability and ease of manipulation.

50 According to the method I have evolved the stock is metered with respect to a relatively fixed cut-off plane, is overfed past this plane to a degree in excess of the amount of stock needed to be metered, and then fed back toward said plane 55 a fixed distance from said plane. These feeding

movements are done by axial end engagement of the bar. The cut-off is in a plane truly transverse to the axis of the bar, but the cut surfaces are at an acute angle to the axis and symmetrically disposed, meeting in an edge which passes 60 through the axis of the bar. Further, according to my method I engage the end of the bar in the metering movement back toward the cut-off plane past which it has been overfed, by engagement with said surfaces.

65 This method I carry out in an apparatus which comprises a bar heating furnace, embodying a bar support within itself, and also embodying a bar support projecting from one of its sides, a rear end bar pusher operating from the opposite 70 side of the furnace to push the bar along the support and out of the furnace, and a front end bar pusher adapted to engage the front end of the bar so as to push it back into the furnace by its end. A cut-off mechanism is located in a plane 75 intermediate the front end bar pusher and the side of the furnace and its support from which the bar emanates from the furnace. The front end bar pusher in its retracted position, acts as a step for the rear end pusher, and in its extended 80 or forward position as the measurer of the stock to be cut. In such capacity it has a limited range of movement, the back end of which defines the limit of forward movement toward the cut-off mechanism of the rear end pusher. Its extreme 85 forward limit of movement toward the cut-off mechanism defines a measured distance with respect to the plane of the cut-off along which and by means of which the length of stock to be cut off is metered. Connected with the front end 90 pusher is a cut-out for the rear end pusher, whereby, when the rear end pusher has pushed the stock to this stop as constituted by the front end pusher, power for the rear end pusher is cut off. Such power is cut on manually or automatically, following the cut-off operation. Normally, the rear 95 end pusher, bar support, metering device and front end pusher lie in series substantially on the same axis. The front end pusher is bodily adjustable along this axis to adjust the position 100 of its limited range of movement on the axis and hence through the relation of its extreme limit of forward movement toward the cut-off plane adjusts the length of the metered stock. It is furthermore adjustable laterally of the axis to 105 move it out of the immediate region of the cut-off mechanism for the purpose of giving the operator access to the cut-off mechanism. Associated with the front pusher and laterally adjustable therewith is the backing-out device also 110

adapted to engage the forward end of the pusher. Like the rear end pusher, it has a pushing range substantially equal to the full length of the furnace whereby a bar irregularly progressed through 5 the furnace or subjected to any other irregularity may be backed into the furnace and started out again regularly. Preferably, this device as disclosed is concentric with the front end pusher and engages the bar on the same axis.

10 The accompanying drawings show the best form of the invention now known to me. Of them,

Fig. 1 is a general side elevation of the entire system with the furnace shown in section on the 15 axis of a bar being fed.

Fig. 2 is an axial cross section of the rear end pusher and its operating mechanism.

Fig. 3 is a similar view of the front end pusher and the cut-off mechanism.

20 Fig. 4 is a plan view of the mechanisms of Fig. 3. Figs. 5 to 9 are diagrams showing the functioning parts of the system.

Figure 10 is an enlarged view of a portion of Figure 3.

25 Figure 11 is a section on the line 11—11 of Figure 2.

Referring first to Fig. 1, 10 is the furnace, 11 is a bar support on the floor of the furnace, 12 an extension thereof projecting out of one side of 30 the furnace, 13 is the rear end pusher mechanism at large, 14 is the cut-off mechanism, 15 is the front end pusher mechanism and 16 is the backing out device.

The furnace itself is diagrammatically shown. 35 It may be any one of the well-known types of bar heating furnaces adapted to heat bars either singly or in multiple, most commonly in multiple. The multiple bar heating furnace heats the bars through reverberatory blasting over the bars as 40 they rest on an inclined furnace floor down which the bars roll by gravity. This furnace is no part of the present invention and has an element in the invention principally because it embodies a means for heating and means of supporting, two 45 elements equivalent of 11 and 12, the bar to be axially fed to cut-off mechanism 14.

The bar support 11 is or may be a part of the furnace floor. If not a part of the furnace floor it must be constituted so that it will stand the 50 extreme heat of the furnace and of the hot bar. It is along this internal support 11 that scale and other refuse collect and ultimately render irregular the support of the bar *b* and bring about its misalignment. As a part of the floor of the furnace the support bears other bars in the heating furnace and these bars, as they bear laterally upon the bar *b* being fed, tend to impart regularity or irregularity in their positions to the bar *b*.

55 The rear end pusher comprises a water cooled bushing rod 17 in axial alignment with the bar *b* and engaging its rear end 18 through an aperture 19 in the rear side of the furnace 10. It is actuated in axial alignment to the axis of the supports 11 and 12 and the bar *b* by an axially 60 aligned rack 18' carried by lower and upper rolls 20 and 21. Water cooled rod 17 constitutes a rigid extension of the bar 18' and its axial alignment is preserved by the preservation of the axial 65 alignment of bar 18' by the pairs of rolls 20, 21. Inlet and discharge water conduits 22 connecting with the rear end of the rod 17 are flexible. The front end of rack 18' is supported and guided by roll 23 running over fixed underlying rail 24. 70 Rack 18', as it is on its underside and is op-

erated to project the push rod 17 into and out of the furnace by a pinion 25 driven from the worm gear 26 connected with the electric motor 27. The rear end of rack 18' runs in rear end guideways 28.

80 Cut-off mechanism 14 may be of any known construction just as in case of the furnace. Suffice it to say that its principal elements, knives 29 act in a plane 30 to symmetrically sever the bar in that plane through the symmetrical approach of their cutting edges 31 in such manner that the inclined faces 32 of the cut are symmetrically disposed and that the final cut-off edge 33 lies on the axis 34 on which the bar and all elements of the system in general lie.

85 Beyond the plane 30 from the furnace lies the front end pusher 15. This front end pusher likewise has its axis on the axis 34. It comprises a reciprocating piston motor 35, the piston 36 of which actuates piston rod 37 which engages the bar *b* on its front or advanced end, as shown in all figures. Motor 35 has a fixed range of movement on the axis 34, that is, to say, a range of movement limited by the stroke of its piston. In its back stroke, piston 36 strikes against the rear end of its cylinder. On its front stroke piston 36 strikes against the front end of its cylinder. In the one case it defines the extreme limit of the backward range of movement and in the other case the extreme 100 range of the forward range of movement.

90 Motor 35 is suspended from a pair of overlying rails 38 by means of front and rear cross heads 39 and 40 slidably connected with these rails. Cross head 39 connects with the rails through the depended angle shaped gibs 41. The cross head connects with the front end of the motor 35 through threaded engagement 42 with its front end, and itself constitutes the front end of the motor cylinder and embodies the stuffing 105 box 43. The rear cross head 40 supports the rear end of the cylinder by a depending journal 44 engaging the backing out device 16. This device 16 has a threaded engagement 45 with the rear cylinder head 46. The front end pusher is 110 bodily axially adjustable with respect to this rear support 40, 44. The rear end pusher 16 intermediate the motor 35 and the support 44 has clamped thereon a collar 47 having a connection with a large screw 48 rotatable in cross 115 head 40 about an axis 49 parallel to the axis 34. Screw 48 is journaled in a bearing 50 in the cross head 40 and is freely rotatable therein by means of a bevel gear connection 51 with a hand wheel 52 operable from a fixed overlying platform 53. 120 Screw 48 being prevented from axial relative movement as respects member 40, when rotated, acts upon the collar 47 to move both the front end pushing device 15 and the backing up device 16 along the axis 34 to bodily adjust them with 125 respect to the plane 30 of the cut-off device 14.

130 Supported from the front cross head 39 by means of forwardly projected rods 54 is a plate 55 carrying a guide 56 for the piston push rod 37. This likewise carries, by an arm 57, a cut-out switch 58 in the circuit of the electric motor 27 of the rear end pusher mechanism of Fig. 2, either directly or indirectly.

135 The backing out device consists of the fluid pressure motor 59 in axial rearward extension of the motor 35 of the front end pusher. A cylinder of this motor is the part which is directly borne in the depending guide 44 of the cross head 40. It is a very long cylinder and its outboard end is borne in a guide 60 in a third cross head 61, like- 140

wise supported from rails 38. Both cross head 40 and this cross head 61 are bolted in suitable position to the rails 38, as shown. Motor 59 has its outboard end closed by a head 62. The inboard end is that which has the threaded connection 45 with the cylinder 35 of the front end pusher 15. A piston 63 of motor 59 operates the piston rod 64, which rod is projected forwardly toward the plane 30 through a hollow piston 36 and the piston rod 37 of the front end pusher, and is adapted to engage the front end of bar b. Piston rod 37 is provided with a rearward extension 65 through the rear cylinder head 46. Between it and cylinder head 46 is a stuffing box 66. Similarly between extension 65 and the piston rod 64 is a second stuffing box 67. The range of movement of the backing out push rod 64 is substantially equal to the full width of the furnace 10, whereby a bar or portion of a bar may be not only pushed back into furnace 10 but also pushed all the way out of the other side through opening 19. Normally, a removable cap 68 on the end of the front end pusher rod 37 precludes engagement of the rod 64 with the work, but this cap may, on occasion, be removed to permit engagement of the work thereby. Cap 68 carries teeth 69 appropriately arranged to engage the work on the well defined and accurately placed face 32 formed by the cut-off knives 29.

Both the front end pusher mechanism 15 and the backing out of pusher mechanism 16 as carried by the rails 38 are laterally adjustable with respect to the axis 34 through the carriage of rails 38 on the head frames 70 and 71 having a wheel support 72 on transverse rails 73. Fluid pressure for forward and back strokes as supplied, the motors 59 and 35 through flexible connections 74, 77, 78, 79, and the exhaust is controlled by any suitable valves, not shown.

The operation is as follows. The bars having been heated in the furnace and the lowermost bar being at that temperature suitable for cutting off the circuit of electric motor 27 is closed through cut-out switch 58 by a switch (not shown) located at any other points in its direct or controlled circuit. The knives 29 being spaced apart sufficiently to allow the front end of the bar b as shown in Fig. 5, the bar b is pushed between them and beyond them on the front side of furnace 10. This pushing out action continues until the front end of the bar engages the front end of the front end pusher rod 37 as appears in Fig. 5 and further until, as appears in Fig. 6, the front end pusher rod 37 has been carried back to its rearward extreme limit of range as defined by the striking of the piston 36 against the rear head of the cylinder 35. At this juncture or slightly before, switch 58 is engaged by the cap 56, (see Fig. 3) and the direct or the control circuit of motor 27 is opened, cutting off the power applied to the rear push rod 17. Thereupon, automatically or by hand, (by means not necessarily shown here) fluid is admitted through the conduit 77 to the rear of piston 36, pushing the bar b back toward the plane 30 of the knives 29 until the extreme forward limit of the range of movement to motor 35 is reached, as shown in Fig. 7. Thereupon, fluid pressure is applied through the conduit 74 to retract front push rod 37 as shown in Fig. 8, and simultaneously but slightly before power is applied to the knives 29 to cut off the section 75 of the stock which has been metered. Thereafter the cycle may be repeated.

It will be apparent that by the backward move-

ment of the front end push device 15, that the action of the knives 29 may take place, without reaction against the rod 33 or cap 68 and thereby so freely as to insure the accurate severing of the length measured. Indeed, the entire bar floats with respect to the powerful knives 29 and the body of the bar no more than the severed front end 75 interferes with the accuracy of action of the knives 29 in their severing of the billet 75 in the plane 30. After the severing of the first billet, the engagement of the accurately formed and symmetrical faces 32 by the teeth 69 of the cap 68 constitutes them an accurate face from which to effect the metering measurement. By reason of the over-feeding by the rear push rod 17, and the re-feeding toward the plane 30 by the metering device 15, as it bears on the symmetrical faces 32 most accurate metering is obtained irrespective of the degree of feeding by the rear push rod 17, this constitutes a much more accurate measure than is constituted by a mere fixed stop for forward movement, with respect to which knives 29 could not act without impairment of their accuracy since there would not be freedom of movement for the billet 75 as cut off. Nor would a switch device 58 utilized to stop the out feeding movement of the bar b accurately stop the bar, for motor 27 would overthrow the bar more or less, depending upon the actual timing of the switch 58 or equivalent device, the resistance of the instant to bar movement, etc.

At any time a scale accumulates, and mis-aligns the bar b or there is any other irregularity in its movement requiring attention, the bar b may be pushed backwards into or out of the furnace 10 sufficiently to clear up the irregularity, as for example, by removal of the scale, by simple adjusting cap 68 to permit rod 64 to push through the end of rod 37 and applying fluid pressure to the rear end of piston 63 to a sufficient extent. Rod 64 is retracted by applying fluid to the opposite side of its piston.

At any time during the operation of the same on or above stock, the length of the metered section 75 may be adjusted merely by turning the hand wheel 52. Any time that the knives 29 or their mechanism 14 needs attention, the entire front end push rod mechanism together with the backing out push rod mechanism 16 may be laterally bodily adjusted by rolling them along the rails 73. In normal operation they are held in place by through bolts or pins 76 bolted in axial alignment.

Modification and improvement are the rule of all inventions. This invention is no exception. Each and all modifications and improvements falling within its generic spirit should likewise fall within the purview of the annexed claims irrespective of the circumstantial terminology which is used.

What I claim is:

1. A hot bar metering system for hot bar cut-off machines comprising a bar support, a rear end bar pusher, a front end bar pusher, and a cut-out for the rear end pusher connected with the front end pusher.

2. A bar metering system for hot bar cut-off machines, comprising a bar support, a rear end bar pusher and front end bar pusher constituting in its retracted position a stop for the rear end pusher, and a cut-cut for the rear end pusher associated with the front end pusher.

3. A bar metering system for bar cut-off machines comprising a bar support, a rear end bar pusher, a front end bar pusher constituting in its

- retracted position a stop for the rear end pusher, and in its forward position a measuring device of the length of the bar to be cut. 8. In combination, a bar support, a bar cut-off mechanism and a front end bar pusher device normally in alignment with the plane of the bar support and adjustable laterally relative to said support. 80
4. A bar metering system for bar cut-off machines comprising a bar support, a rear end bar pusher, a front end bar pusher constituting in its retracted position a stop for the rear end pusher, and in its forward position a measuring device of the length of the stock to be cut, a bar cut-off device forward of the extreme limit of forward movement of the front pusher. 9. A bar metering system comprising a bar support, a bar cut-off in advance of said support, a rear end bar pusher having an unlimited range of push movement within the range of length of the bar past the cut-off mechanism, and a front end pusher beyond the cut-off mechanism from the bar support having a fixed range of movement forward and back, whereby on its back stroke it may act as a stop for said rear pusher, and in its forward stroke it measures the length of the bar between the cut-off mechanism itself. 85
5. A bar metering system for bar cut-off machines comprising a bar support, a rear end bar pusher, a front end bar pusher constituting in its retracted position a stop for the rear end pusher, and in its forward position a measuring device of the length of the stock to be cut, a bar cut-off device forward of the extreme limit of forward movement of the front pusher, and means to shift the front end pusher bodily to adjust the metering of the bar. 10. A bar metering system for hot-bar cut-off machines comprising a bar support, a rear-end bar pusher, a front-end bar pusher, said front end pusher including elemental parts movable simultaneously and relatively to each other and a cut-out responsive to the relative movement of said front end pusher parts for controlling the operation of the rear-end pusher. 90
15. retracted position a stop for the rear end pusher, and in its forward position a measuring device of the length of the stock to be cut, a bar cut-off device forward of the extreme limit of forward movement of the front pusher, and means to shift the front end pusher bodily to adjust the metering of the bar. 11. A bar metering system for hot-bar cut-off machines comprising a bar support, a rear-end bar pusher, and a front-end bar pusher including axially-aligned pistons movable in concert and relative to each other. 100
20. 6. A hot bar feeding system for hot bar cut-off devices comprising a furnace, a bar support connected with the furnace, a rear end bar pusher adapted to push the hot bar from the furnace to be cut off and having a range of movement extending substantially the complete width of the furnace, together with a bar backing out pusher on the cut-off side of the furnace adapted to engage the forward end of the bar and having a range of operative movement also substantially the complete width of the furnace. 12. A hot bar metering system for hot bar cut-off machines comprising a bar support, a rear end bar pusher, a front end bar pusher, a cut-out for said rear end pusher connected with said front end pusher, and cut-off means interposed between said front end and rear end pushers, and vernier means associated with said front end pusher, whereby to pre-determinately control a relative movement of said front end pusher with respect to said cut-off means. 105
25. 7. A bar metering system for hot bar cut-off machines comprising a furnace, a bar support within and projecting from the furnace, a rear end bar pusher adapted to push the bar over its support and out of the furnace, a front end bar pusher connecting in its extreme forward position as the measure up of the stock to be 110 cut with respect to the cut-off mechanism, and a backing out device adapted to engage the front end of a bar concentric with the front end pusher. 120
30. 45. 50. 55. 60. 65. 70. 75. 80. 85. 90. 95. 100. 105. 110. 115. 120. 125. 130. 135. 140. 145. 150. 155. 160. 165. 170. 175. 180. 185. 190. 195. 200. 205. 210. 215. 220. 225. 230. 235. 240. 245.
